H. H. TIMKEN,
CUP FOR ROLLER BEARINGS AND PROCESS OF MAKING SAME.
APPLICATION FILED APR. 15, 1918.

1,326,224.

Patented Dec. 30, 1919.

Inventor:
Henry H. Timken,
by Constantine
his attorney.

UNITED STATES PATENT OFFICE.

HENRY H. TIMKEN, OF CANTON, OHIO.

CUP FOR ROLLER-BEARINGS AND PROCESS OF MAKING SAME.

1,326,224.

Specification of Letters Patent. Patented Dec. 30, 1919.

Application filed April 15, 1918. Serial No. 228,592.

To all whom it may concern:

Be it known that I, HENRY H. TIMKEN, a citizen of the United States, and a resident of the city of Canton, in the county of Stark and State of Ohio, have invented a new and useful Improvement in Cups for Roller-Bearings and Processes of Making Same, of which the following is a specification.

My invention relates to a process of manufacturing cups for conical roller bearings. Heretofore, the cup has been an expensive item in the manufacture of roller bearings, because of it involving so much skilled work, so much waste of material and so much loss of product due to inaccuracies and distortions occasioned by heat treatment or by insufficiently accurate workmanship.

The principal objects of the present invention are to simplify the process of manufacturing conical bearing cups, to reduce the cost of manufacture, and to minimize the danger of distortion in the heat treatment.

In the accompanying drawing, which forms part of this specification, and wherein like symbols refer to like parts wherever they occur.

Figure 1 is an end view of a cylindrical tube constituting the stock from which the bearing cup is formed;

Fig. 2 is a side view of the tube, with dotted lines indicating where sections or rings are to be cut therefrom;

Fig. 3 is a side view of one of said sections or rings;

Fig. 4 is a vertical sectional view of the die with the section or ring in initial position therein and with the punch shown in side elevation and in raised position;

Fig. 5 is a vertical sectional view through the die, punch, and cup or ring showing the punch at the downward limit of its stroke;

Fig. 6 is a sectional view of a finished cup or ring of uniform thickness;

Fig. 7 is a vertical section of a cup or ring wherein the inclination of the inner surface is greater than the inclination of the outer surface;

Figs. 8 to 12, inclusive, illustrate various stages of manufacture of a bearing cup out of a flat sheet.

Fig. 8 is a cross-sectional detail of a sheet metal blank used as a stock for the manufacture of a bearing cup;

Fig. 9 is a cross-section of said blank after the completion of the drawing operation thereon;

Fig. 10 is a similar view of the partially completed cup after the bottom has been punched therefrom;

Fig. 11 is a similar view showing the cup with its upper edge trimmed; and

Fig. 12 shows the cup with its lower edge trimmed.

Heretofore, it has been the common practice in the manufacture of conical bearing cups to start with a suitable blank, bore out the interior thereof, and work the inner surface to the desired shape, harden the same by proper heat treatment, and then finish by grinding. A common result of the heat treatment under the old process was to warp or distort the cup so much that the grinding operation would entirely grind away considerable areas of the hardened surface; in fact, the distortion would sometimes be so great as to necessitate the scrapping of the cup.

According to the present invention, it is preferable to start with a seamless tube A of drawn steel of cylindrical section. This tube is cut into short lengths or rings A¹ of approximately the length of the finished cup, or a little less. Both the inner and the outer surfaces of this ring are made approximately cylindrical and concentric so as to have a wall of even thickness throughout. In order to obtain accuracy and concentricity of the inner surface at small expense, it is preferred to ream out the interior of the ring or short length of the tube to a diameter very slightly less than required, and then simply finish the same by broaching in a press.

At this stage of manufacture, the ring A¹ is a cylinder; and the next operation is to convert this cylinder into a true conical cup with its inner and outer surfaces concentric. This result can be accomplished either by expansion or by contraction of the cylinder, the latter being preferred. For the purpose of contracting the cylinder into a cone, the cylindrical ring A¹ is forced endwise in a strong tapering die C whose operative inner surface 1 is of conical form and of a diameter which ranges from a little more than the overall diameter of the ring at the top of the die to the overall diameter of the finished

cone at the bottom of the functional surface of the die, by which is meant so much of the surface as the ring rubs against.

- Mounted on or integral with the plunger
- 5 D, which applies the force to the end of the ring, is a mandrel 3 arranged in axial alignment with the die and whose exterior surface is a cone of the size and inclination of the interior of the finished cup. When the ring
- 10 A¹ is placed in the die and pressure applied thereto by means of the plunger, the effect is to force the ring inwardly of the die. This operation contracts the diameter of so much of the ring as comes in contact with
- 15 the inner surface of the die, so as to conform the outer surface of the ring to the inner surface of the die; and at the same time, the inner surface of the ring is made to conform to the outer face of the mandrel. The cup is
- 20 loosened from the die by a suitable knock-out E. When the surface of the mandrel has the same inclination as the inner surface of the die, the effect of this operation is to convert the cylindrical ring of uniform
- 25 thickness into a cone A² of the required size and shape and of even thickness throughout as illustrated in Fig. 6. But, if the inclination of the surface of the mandrel is different from the inclination of the inner surface
- 30 of the die, the metal will be forced to fill up the annular space between the mandrel and the die so as to produce a cup A³ whose inner surface conforms to the inclination of the mandrel and whose outer surface conforms
- 35 to the inclination of the die as illustrated in Fig. 7. In either case, the surfaces of the cup are accurately enough finished to make it unnecessary to do further work on them before hardening or carbonizing. The cup
- 40 is now ready for such minor or incidental operations as "radiusing" or rounding the inner edges and chamfering or otherwise fitting the end for coöperation with other members; but such operations do not form
- 45 part of this invention.
- The next step is to carbonize the cones or cups in the usual manner or submit them to any of the usual heat treatments for the purpose of hardening them. As these conical
- 50 cups are of circular section and have walls of even thickness throughout or walls whose thickness varies quite gradually, the tendency is for them to distort very little, if any, during the heat treatment; and the form of
- 55 the cup makes it a simple matter to correct minor irregularities arising from warping. Consequently, there is practically no loss of the product due to the heat treatment, and very little, if any, occasion to grind the hardened surface. In other words, the grinding operation heretofore commonly required may be dispensed with entirely. Besides, the form of the cups allows different sizes to be nested during the heat treatment and thereby effects considerable saving. This

capacity for nesting also effects an economy in storing and shipping.

The principal advantage in contracting the ring, rather than expanding it, is that the contraction avoids the severe tensile 70 stress that might disrupt the wall. Besides, the operation of the contracting is better adapted for rectifying any unevenness in the thickness of the wall and it tends to make the metal more compact.

While it is preferable to start with cylindrical tubing A, it is practicable to start with a solid blank or with a flat strip B of metal. It is preferable to accurately finish both surfaces of the flat strip. The blank is 80 then cut from the strip and placed in a forming die and drawn into the form of a conical cup B¹. The bottom of the cup is then punched out forming a cone B² as illustrated in Fig. 10. The top of the cone B³ 85 (see Fig. 11) and the bottom of the cone B⁴ (see Fig. 12) are then trimmed to produce the required dimensions for the finished cup. The conical cup is then hardened and, if a very highly finished surface is required, it 90 may be slightly ground also. On account of the form of the cup, there is not likely to be any considerable distortion caused by the heat treatment.

What I claim is:

1. The process of making conical cups for roller bearings which consists in forming cylindrical rings, then die-shaping said rings into conical cups and then completing said cups by suitable heat treatment to harden 100 the same without other finishing after heat treatment.

2. The process of making conical cups for roller bearings which consists in forming a cylindrical ring, die-shaping said ring into a 105 conical cup of less diameter than said cylindrical ring and then completing said cup by suitable heat treatment to harden the same without other finishing.

3. The process of making conical cups for roller bearings which consists in forming a cylindrical ring, die-shaping said ring into a 110 conical cup of less diameter than said cylindrical ring, and then completing said cup by suitable heat treatment to harden the same 115 without other finishing.

4. The process of making conical cups for roller bearings which consists in forming a cylindrical ring, die-shaping said ring to a 120 conical cup, completing said cup by suitable heat treatment to harden the same, and then finishing by grinding or other suitable finishing process.

5. The process of making conical cups for roller bearings which consists in forming cylindrical rings of approximately even 125 thickness, finishing the inner surface of said rings, and then die-shaping said rings into conical cups with walls of even thickness.

6. The process of making conical cups for 130

5 roller bearings which consists in forming cylindrical rings of approximately even thickness, die-shaping said rings to conical cups with walls of even thickness, and then completing said cups by suitable heat treatment to harden the same without other finishing after heat treatment.

10 7. The process of making cups for roller bearings which consists in cylindrically reaming the inside of a piece of cylindrical metal tubing and finishing the outside concentric therewith, and then forcing said piece endwise into a tapering die whereby a conical cup is formed with smooth and den-
15 sified surface.

20 8. The process of making cups for roller bearings which consists in cylindrically reaming the inside of a piece of cylindrical metal tubing and finishing the outside concentric therewith, forcing said piece endwise into a tapering die, whereby a conical cup is formed with smooth and densified surface, and then completing said cup by suitable heat treatment to harden the same without
25 other finishing operation.

9. The process of making cups for roller bearings which consists in reaming and broaching the inside of a piece of cylindrical

metal tube, finishing the outside concentric therewith, forcing said piece endwise into a 30 taper die whereby a conical cup is formed with a smooth and densified surface, heat treating said cup and completing said cup by removing by any suitable treatment the bur left on the ends of the cup after the 35 die-shaping operation.

10. As a new article of manufacture, a conical cup for roller bearings resulting from the contraction of a finished ring by movement endwise in a suitable contracting 40 mandrel.

11. As a new article of manufacture, a conical cup for roller bearings resulting from the contraction of a finished cylinder of even thickness by movement endwise in a 45 contracting mandrel.

12. As a new article of manufacture, a conical cup for roller bearings, resulting from the contraction of a finished cylinder of even thickness by movement endwise in a 50 contracting mandrel, said product being hardened but not ground.

Signed at Canton, Ohio, this 10th day of April, 1918.

HENRY H. TIMKEN.
